UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE-SEPARATING MEANS.

Application filed February 6, 1922. Serial No. 534,540.

To all whom it may concern:

Be it known that I, RICHARD LESTER WILCOX, a citizen of the United States, residing at Waterbury, in the county of New Haven and State of Connecticut, have invented certain new and useful Improvements in Die-Separating Means, of which the following is a specification, reference being had therein to the accompanying drawings.

10 My invention relates to die separating means, its principal object being to provide simple mechanism for separating the dies of an open die header or upsetting machine.

15 Among other aims and objects of my invention may be recited the provision of a device of the character mentioned with a view to compactness and in which the number of parts are few, the construction simple, the cost of production small, and efficiency and operation high.

20 The improvements in the details and arrangement of parts will be apparent from an inspection of the accompanying drawings, in connection with the description hereinafter contained, and wherein an embodiment of the invention is disclosed for the purpose of imparting a full understanding of the same.

Having more particular reference to the 30 drawings and in connection with which like reference characters refer to corresponding parts in the several figures;

Figure 1 is a front view of a pair of dies of a heading machine or the like and a fragmentary portion of its supporting mechanism, with my improved means connected therewith;

Figure 2 is a sectional elevation thereof taken generally upon line 2—2 of Figure 1;

40 Figure 3 is a detail sectional view of the mechanism taken generally upon line 3—3 of Figure 2;

Figure 4 is a detail sectional view, similar to Figure 3, illustrating a modified structure;

45 Figure 5 is a fragmentary sectional elevation, similar to Figure 2, illustrating a modified structure; and

Figure 6 is a front view of a pair of dies, and adjacent mechanism, similar to Figure 1, but illustrating an alternative structure.

It has heretofore been the practice to separate the dies of an open die header or upsetting machine at the wire feed line by

parting pins, separating pins or the like, an 55 illustration of such means being shown in Letters Patent No. 1,104,090, dated July 21, 1914, particularly in Figure 4 thereof, and also in Letters Patent No. 1,108,958, dated September 1, 1914, a heavy flat spring, not 60 shown in either of the above patents, bearing upon the upper end of each of the parting pins or separating pins, which move in a path at substantially a right angle to the movement of the dies. With such mechanism the die cap or other part or parts that support the pins must be machined with 65 great care and exactness and each must be in correct alignment with each other and the groove formed by the angular corner faces 70 of the dies, when the dies are in proximity to the wire feed line. If the pins are not so arranged, the lower pointed end thereof will not register with said groove, thus having 75 a tendency to cramp the dies and apply an unequal pressure thereto at different points throughout their length. If this occurs, the dies may be separated more at one end than at the other, and if perchance the 80 minimum separation is at the inner end of the dies a defective feed of the wire results and the end of the wire may abut against the dies and stop the feed.

With the use of such pins the spring pressure upon the end thereof is constant, therefore it requires not only a pressure sufficient to move the dies and cut off the wire but also to resist the pressure of the pin actuating springs, which pressure is constant upon the top of one of the dies during its entire movement. There is no use for this pressure except when the dies are to be separated at the wire feed line, hence more power is necessarily required to actuate the dies. While more powerful mechanism is required to 95 move the dies from the wire feed line to the upsetting line, the dies are usually returned by spring pressure, the strength of which must of necessity also be increased to overcome the needless drag and pressure of the 100 pins.

As the pins are of substantial length the element in which they are mounted must of necessity be of substantial height to provide proper support therefor and this height, as 105 well as the pin operating springs, requires space that can otherwise be advantageously utilized.

All of the above and other objections of the heretofore conventional method for separating the dies are obviated in my improved device, which occupies the minimum amount 5 of not otherwise required space, pressure is applied only when the dies are to be separated, the necessity of fine machining of the parts is entirely eliminated, and in these, and many other ways, produces results that are 10 advantageous and insure certainty and efficiency in operation, and with mechanism that is of comparatively simple design.

Having more particular reference to the drawings, numerals 10 and 11 represent the 15 dies, which are of the usual form with corner angular faces 12 which unite to form a V shaped groove substantially as shown in Figures 1 and 3, wherein the dies are adjacent to the wire feed line near the 20 line 2—2 of Figure 1. A piece of wire designated 13 is shown in section at this feed line.

The bed plate upon which the dies are supported in designated 14, and the cap 25 or cover over the top thereof 15.

All of the mechanism above described is of a well known form and operates in an equally well known manner and therefore needs no further description herein.

30 The means for actuating the dies is not shown herein for the above reason, but the same travel between the wire feed line and the upsetting line, which latter line is designated $\alpha-\alpha$ in Figure 1. From the wire feed line 35 to the upsetting line the dies are positively actuated by relatively powerful mechanism to cut off a piece of the wire rod but are usually returned from the upsetting line by spring mechanism.

40 Referring now particularly to Figures 1, 2 and 3, the bed plate 14 is provided with an opening 16 having one angular wall 17 and an adjacent wall 18 separated by a recess 19 within which is a block 20 which 45 is loosely mounted and moved in one direction by one or more springs 21 and having a circular recess 22 in the top thereof. A plate 23 preferably rounded at each end is supported by the block 20 with one of its 50 rounded ends in the circular recess 22 substantially as shown in Figure 3. Endwise movement of this block and plate within the opening 16 is prevented by the cap 24 connected with the bed plate, or by other suitable means.

The position of the plate 23 is shown by full lines when the dies are at rest near the wire feed line, at which time the upper rounded end of said plate is within the 60 V groove formed by two of the angular faces 12 of the dies 10 and 11 and the lower rounded end is within the recess 22 of the block 20.

When the parts are so arranged the dies 65 10 and 11 are a slight distance apart so as

to admit a proper feed of the wire 13 therebetween. As the dies move from this position to the upsetting line, the plate 23 rocks therewith until it assumes the position in the opening 16 substantially as shown by 70 broken lines in Figure 3.

The pressure of the springs 21 upon the block 20 and through it upon the plate 23 is such as to always maintain the lower end of said plate in contact with said block and 75 the upper end with one or both of the adjacent angular faces 12 of the dies 10 and 11, thus insuring a constant contact of the said plate.

When the dies are returned from the upsetting line to the wire feed line and are approximately at the latter line, the lower rounded end of the plate 23 fulcrums in the curved recess 22, which is now rigid against the bottom 25 of the recess 19, and 85 moves the upper rounded end upwardly a limited distance and forces the dies apart the required distance. With this improved separating mechanism only the minimum amount of space is required, pressure is 90 only applied when the dies are at or near the wire feed line, and in these and other ways, the objections to the mechanism heretofore commonly utilized for separating the dies are eliminated and many obvious 95 advantages secured.

A plurality of blocks 20 and plates 23, each in a separate recess may also be substituted for a single block and plate, if desired, substantially as shown in Figure 5, 100 the bed plate 14^a being suitably formed for this purpose.

I have shown herein my improved mechanism as applied to the underside of the dies but obviously it will operate equally 105 as well if applied to the top side thereof, or if desired, it may be used upon both top and bottom as shown in Figure 6. When applied to the top side of the dies, the cap or cover 15^a is so constructed as to receive 110 the block 20, plate 23, and cap 24, all of which are as above described.

The ends of the plate 23^a may, if desired, be V-shaped or otherwise formed as illustrated in Figure 4, instead of rounded as above described, in which case the block 20^a is shaped to accommodate this changed structure.

There are minor changes and alterations 120 that can be made within my invention, aside from those herein suggested, and I would therefore have it understood that I do not limit myself to the exact construction herein shown and described, but claim all that falls fairly within the spirit and scope of 125 the appended claims.

Having described my invention, what I claim as new and desire to secure by Letters Patent, is:

1. In combination with dies of a heading 130

machine or the like, of means for separating the same at a predetermined point, comprising a plate within an adjacent recessed member, in contact with and moved by said dies, a block movable within said member, and means for holding the same in contact with said plate.

2. In combination with dies of a heading machine or the like, of means for separating said dies, comprising a rock member within an adjacent recessed member, a second member, and means for mounting the same in said recessed member whereby it will maintain contact with said plate irrespective of the position of said plate within said recessed member.

3. In combination with the dies of a heading machine or the like, of a recessed member adjacent thereto, a plate movable within the recess in said member, a block movable in said recess and having contact with said plate, and means for holding said block in contact with said plate during the entire movement of the latter by said dies.

4. In combination with the dies of a heading machine or the like, of a recessed member adjacent thereto, a block mounted within the recess in said member, yielding means for moving said block in one direction, and a plate having contact with said block and dies.

5. In combination with the dies of a heading machine or the like, of a recessed member adjacent thereto, a block movably mounted within the recess in said member, yielding means for moving said block in said recess toward said dies, and a plate having contact at one end with said block and at the other end with the walls of the notch formed between said dies.

6. In combination with the dies of a heading machine or the like, means for supporting the same, and means for separating said dies, comprising a rock member within a

recessed member, a fulcrum block in said recessed member, and means for mounting said fulcrum block whereby it will maintain contact with said rock member irrespective of its relative position in said recessed member.

7. In combination with the dies of a heading machine or the like, of a recessed member adjacent thereto, a plate having rounded ends movable within the recess in said member, a block having one recessed face to receive one of the rounded ends of said plate, and means for mounting said block whereby it will maintain contact with said plate irrespective of its relative position in said recessed member.

8. In combination with the dies of a heading machine or the like, so shaped that when adjacent to each other a groove is formed therebetween at one edge thereof, of a recessed member adjacent thereto, a block within said recessed member, a rock member having engagement at one end with said groove and at the other end with said block, and means for maintaining said block in contact with said rock member, during the entire movement of said dies.

9. In combination with the dies of a heading machine or the like, so shaped that when adjacent to each other a groove is formed therebetween at one edge thereof, of a recessed member adjacent thereto, a block within said recessed member, a rock member rounded at each end, one of said rounded ends having a pivotal connection with the said block and the other projecting into said groove, and means for actuating said block so that said rock member will maintain contact with said dies during the entire movement thereof.

In testimony whereof, I have hereunto affixed my signature.

RICHARD LESTER WILCOX.
